United States Patent

Des. 236,087
Patented July 29, 1975

236,087

BOTTLE

Richard L. Gannett and Jeffrey L. Ashby, Dallas, Bruce E. Welsh, Jr., and Daniel A. Leo, Richardson, and Carlton W. Howorth, Dallas, Tex., and Robert E. Cobra, Racine, Wis., assignors to Anderson, Clayton & Co., Houston, Tex.

Filed Sept. 29, 1972, Ser. No. 293,357

Term of patent 14 years

Int. Cl. D9—01

U.S. CL. D8—28

FIG. 1 is a front elevational view of a bottle, showing my new design;

FIG. 2 is a bottom view thereof;

FIG. 3 is a top plan view thereof; and

FIG. 4 is an elevational view thereof looking from the right of FIG. 1.

We claim:

The ornamental design for a bottle, substantially as shown.
